(57) **CLAIM**

The ornamental design for a bottle, as shown and described.

DESCRIPTION

FIG. 1 is a front view of a bottle showing a first embodiment of the design.

FIG. 2 is a left view thereof.

FIG. 3 is a rear view thereof.

FIG. 4 is a right view thereof.

FIG. 5 is a top view thereof.

FIG. 6 is a bottom view thereof.

FIG. 7 is a front view of a bottle showing a second embodiment of the design.

FIG. 8 is a left view thereof.

FIG. 9 is a rear view thereof.

FIG. 10 is a right view thereof.

FIG. 11 is a top view thereof; and,

FIG. 12 is a bottom view thereof.

The broken lines in the drawings represent portions of the bottle that form no part of the claimed design.
